UNITED STATES PATENT OFFICE.

WILLIAM C. GURNEY, OF TORONTO, ONTARIO, CANADA, ASSIGNOR TO GURNEY HEATER MANUFACTURING COMPANY, OF BOSTON, MASSACHUSETTS, A CORPORATION OF MASSACHUSETTS.

SMOKE-CONSUMING BOILER.

1,198,838.

Specification of Letters Patent. Patented Sept. 19, 1916.

Application filed April 9, 1915. Serial No. 20,280.

To all whom it may concern:

Be it known that I, WILLIAM CROMWELL GURNEY, of the city of Toronto, in the county of York and Province of Ontario, Dominion of Canada, have invented certain new and useful Improvements in Smoke-Consuming Boilers; and I hereby declare that the following is a full, clear, and exact description of the same.

In my application for Letters Patent of the United States, Serial #845,326, filed June 15th, 1914, I have shown and described a smoke consuming boiler comprising a set of assembled boiler sections inclosing a furnace comprising a fuel chamber provided with a hollow water grate consisting of two or more separated sets of grate sections with an unoccupied space between them, whereby the sections of each set can expand and contract independently of each other as a result of the variations of temperature therein and a fire chamber located below the hollow water grate in which the combustion of the gas from the fuel chamber occurs.

My present invention relates to an improvement in the construction of the smoke consuming boiler forming the subject matter of the above application, and this improvement consists of making the grate of tubular bars arranged in two or more aligned sets of grate sections spaced lengthwise of the furnace so that the tubular bars of each grate section can expand and contract independently of the tubular bars of the opposed grate section; one of the objects of the invention being to facilitate the stoking of the furnace which is effected by forming, through the boiler casing, apertures in line with the intervals between the tubular bars so that when a poker is inserted through these apertures it will loosen the fuel supported upon the grate, for its descent through the intervals between the grate bars to the fire chamber below.

A further object of the invention is to so arrange the boiler sections in rear of the furnace that the burnt gas will be forced to take a staggered course to the smoke outlet, as hereinafter described and more particularly pointed out in the claim.

In the drawings:—Figure 1, is a front elevation of the boiler, with the furnace doors removed; Fig. 2, is a transverse section of the same on the line *a—a*, Fig. 4, with the rocking grate bars omitted; Fig. 3,

is a similar view to Fig. 2, on the line *b—b*, Fig. 4; and, Fig. 4, is a longitudinal section on the line *c—c*, Fig. 1.

Like characters of reference refer to like parts throughout the specification and drawings.

The boiler comprises a base *a* having a doorway *b* into the ashpit *c* for draft and cleaning purposes; the base *a*, in rear of the ashpit, having a wall *d* separating it from the combustion chamber *q*. Mounted on the base *a* is the boiler front *f* which, as shown in Fig. 4, forms one of the water sections of the boiler. Supported upon the base *a*, in rear of the front *f*, are arched water sections *g* which, together with the boiler front *f* and bridge wall *l*, inclose the boiler furnace consisting of the fuel chamber *h* and the fire chamber *i*. Formed through the boiler front *f* is a doorway *j* for the fuel chamber *h* and a doorway *k* for the fire chamber *i*, and at the bottom of the fire chamber *i* is a set of rocking grate bars *m*.

Connected with the water spaces *f'* of the boiler front is a set of laterally spaced tubular grate bars *o* forming one of the grate sections and connected with the water spaces *l'* of the bridge wall *l* is a set of laterally spaced tubular grate bars *o'* forming the other grate section; the tubes *o*, *o'* being opposed to and in line with each other with an unoccupied space *o''* between them so that they can expand and contract independently of each other as a result of the variations of temperature in the furnace, thus avoiding any liability on the part of the water grate to strain the boiler sections; the lateral spacing of the grate bars providing intervals through which the contents of the fuel chamber may pass into the fire chamber.

Formed through the bridge wall *l*, below the water grate, are passages *p* leading from the fire chamber *i* into the combustion chamber *q*.

In rear of the bridge wall are boiler sections *r*, *r'*, *r''*, *r³* and *r⁴* supported upon the base *a*, in rear of the partition wall *d*. In the boiler section *r* is a hollow baffle wall *s* forming part of that boiler section, with a combustion chamber *q* between it and the bridge wall *l*. The baffle wall *s* extends from the base *a* to nearly the top of the boiler section so that the products of combustion entering the combustion chamber *q*

will be deflected upwardly to the passage *t* at the top of the baffle wall and then into the combustion chamber *q'* between the baffle wall *s* of the boiler section *r* and the 5 baffle wall *s'* of the adjoining boiler section *r'*, the movement of the products of combustion from the combustion chamber *q* through the base being prevented by the partition wall *d'* extending downwardly from the 10 bottom of the baffle wall *s* to the bottom of the base. The baffle wall *s'* forms part of the boiler section *r'* and extends downwardly from the top of that boiler section so that the movement of the products of 15 combustion will be through the passage *p*, upwardly through the combustion chamber *q*, horizontally through the passage *t*, downwardly through the combustion chamber *q'*, horizontally around the bottom of the baffle 20 wall *s'*, upwardly through the combustion chamber *q''*, horizontally across the top of the baffle wall *s''*, downwardly through the combustion chamber *q³*, horizontally across the lower end of the baffle wall *s³* and then 25 upwardly through the combustion chamber *q⁴* to the smoke outlet *u*, partition walls *d''* and *d³* extending downwardly from the lower ends of the baffle walls *s''* and *s⁴* to the bottom of the base for the purpose of 30 causing the products of combustion to take the above described course; the baffle wall *s⁴* in the present construction forming the back of the boiler.

In each of the combustion chambers *q*, *q'*, 35 *q''*, *q³*, and *q⁴* are doorways *v* which permit of the products of combustion being viewed as they pass from the fire chamber *i* to the smoke outlet *u* and also to permit of the combustion chambers being cleaned; the 40 ashes and soot therein falling into the base which is provided with doorways *v'* for the removal of the contents thereof.

The fuel, when introduced through the doorway *j* into the fuel chamber *h*, is supported upon the grate formed by the tubular bars *o*, *o'*, and when ignited the gas passes downwardly through the intervals between the tubular bars and is burnt within the fire chamber *i*, the coked fuel within 45 the fuel chamber *h* also descending through the intervals between the tubular bars into the fire chamber and resting upon the grate 50

bars *m* where a secondary combustion is maintained to effect the complete combustion of the burning fuel in the fire chamber 55 and the gas descending from the coking fuel in the fuel chamber. In the event of the intervals between the grate bars becoming choked, the introduction of a poker through the apertures *w* will break up the mass, part 60 of which, in the vicinity of the tubular bars descending through the intervals between them to the fire chamber *i* and finding a lodgment upon the grate bars *m*. The apertures *w*, as shown in Figs. 1 and 4 are located in line with the intervals between the tubular bars and slightly above the same which permits of the insertion of a poker 65 and its unimpeded movement from the boiler front to the bridge wall *l* thus materially facilitating the stoking of the boiler. 70

It has been ascertained from actual use of this boiler that soft coal, even when the fire is first started, gives off no visible smoke, the combustion of the fuel being practically 75 perfect; this being effected by the downward course of the gas from the fuel chamber through the fire chamber to the combustion chamber, and the staggered course through the combustion chambers to the smoke outlet. 80

What I claim is:

A boiler comprising a hollow base and a set of assembled boiler sections inclosing a furnace and vertical combustion chambers 85 with hollow baffle walls forming part of the boiler sections arranged within the combustion chambers having passages alternately at the top and bottom of the boiler sections for a staggered circulation of the products 90 of combustion from the furnace to the smoke outlet, and partitions extending downwardly from each alternate baffle to the bottom of the base, the boiler sections having covered openings into the combustion 95 chambers and the base having covered openings into each compartment formed by the partitions.

Toronto, April 5th, 1915.

WILLIAM C. GURNEY.

Signed in the presence of—

C. H. RICHES,
EDWARD S. BERNSTEIN.
